Application filed March 10, 1906. Serial No. 305,409. Term of patent 3½ years.

To all whom it may concern:

Be it known that I, MYRON W. WILKINS, a citizen of the United States, residing at Gloversville, in the county of Fulton and State of New York, have invented and produced a new, original, and ornamental Design for a Purse; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 is a side elevation illustrating my new design, and Fig. 2 is a front elevation of the same.

As shown in the drawings, the leading or material feature of my design consists in an

ornamental purse having at its front portion a miniature representation of an automobile.

In said drawings, *a* indicates an ornamental purse of my new design, having at its front the representation of a miniature automobile *b*.

c represents the bottom of the cap, which constitutes the purse opening, such opening being completely circular, and *d* represents the vizor of the cap, which is completely independent of the opening.

I claim:

The ornamental design for a purse, as shown and described.
